NEWSPAPER DISPENSING MACHINE

John Edward Opgenorth, Alameda, Calif.

Application August 16, 1948, Serial No. 44,487

8 Claims. (Cl. 312—55)

1

This invention relates to, and it is an object to provide, a novel machine for dispensing newspapers, one at a time, to customers.

Another object of the invention is to provide a newspaper dispensing machine which includes a newspaper feeding unit arranged in reciprocating relation within a housing and in cooperative relation to a stack of newspapers therein, feeding one newspaper from the housing with each reciprocation of said unit; the latter being manually actuated by the customer.

A further object of the invention is to provide a newspaper dispensing machine, as in the preceding paragraph wherein the newspaper feeding unit is of novel design operative to function successfully in connection with a stack of newspapers which diminishes in height as the newspapers are successively dispensed from the top of said stack.

An additional object of the invention is to provide a newspaper dispensing machine wherein the aforesaid reciprocating newspaper feeding unit has a constant length of travel or stroke regardless of the height of the stack of newspapers; this being essential to proper feeding of each newspaper from the top of the stack and thence into the delivery chute.

It is also an object of the invention to provide a newspaper dispensing machine which includes a glass faced, display chamber at the front of the housing adapted to receive a newspaper of the edition being dispensed by the machine; there being mechanism operative to dispense said displayed newspaper after the last one of the stack in the housing has been dispensed. This empties the display chamber and indicates to subsequent prospective customers that the machine is empty and out of service.

A further object of the invention is to provide a practical newspaper dispensing machine which will be exceedingly effective for the purpose for which it is designed.

These objects are accomplished by means of such structure and relative arrangement of parts as will fully appear by a perusal of the following specification and claims.

In the drawings:

Fig. 1 is a longitudinal sectional elevation of the newspaper dispensing machine.

Fig. 2 is a plan view of the newspaper feeding unit, detached.

Fig. 3 is a cross section taken through the assembly of the platform and supporting rails, showing the position of the newspaper feeding unit after the last newspaper of the stack has been dispensed.

2

Fig. 4 is a fragmentary side elevation, partly in section, of the newspaper feeding unit in the position of Fig. 3.

Fig. 5 is a diagrammatic perspective view of 5 the carriage actuating mechanism including the flexible cord system.

Fig. 6 is a diagrammatic perspective view of 10 the gate and the releasable holding mechanism therefor, which maintains a newspaper in the display chamber.

Referring now more particularly to the characters of reference on the drawings, the machine comprises an upstanding rectangular frame, indicated generally at 1, which frame is enclosed 15 generally at 1, which frame is enclosed by a housing 2; the latter including a top plate 3, a front wall 4, and a back wall 5. Within the housing 2 there is a front stop plate 6 and a back stop plate 7 disposed in adjacent spaced relation rearwardly of the front wall 4, and in adjacent 10 spaced relation ahead of the back wall 5, respectively.

The space between the front wall 4 and front stop plate 6 forms a display chamber for the 20 reception of one copy of the edition of the newspaper being dispensed by the machine. The front of the display chamber 8 is in the form of a glass window 9 included in the front wall 4. The display newspaper 10 in the chamber 8 is placed 25 in the latter by means of a top door 11, such display newspaper being supported along its lower edge by means of a rotary horizontal gate 12 normally latched in closed position, as will 30 hereinafter appear.

The normally closed gate 12 is at the top of a 35 newspaper delivery opening 13 in the front of the housing 2 adjacent the bottom thereof; said newspaper delivery opening 13 being much higher than the thickness of the ordinary newspaper and substantially the full width of said housing 2.

A chute 14 is mounted in approximately the 40 front half of the housing 2 and extends from a cross member 15 at a forward and downward slope through the delivery opening 13 at the bottom of the latter; said chute 14 being formed, at its lower edge and exteriorly of the front of the housing 2, with upturned stop fingers 16.

A platform 17 extends from the back wall 5 at 45 a forward and upward incline to the cross member 15; such platform being for the reception of a stack 18 of newspapers, with their folded edges rearmost, as shown in Fig. 1.

The forward edge of the platform 17 is disposed 50 above the rear end of the chute 14, and the inclination of such platform is for the purpose of assuring that the newspapers of the stack 18 tend

to remain in position in engagement with the back wall 5 when the uppermost one of the newspapers of the stack is dispensed in the manner hereinafter described.

The following newspaper feeding unit is included in the machine for the purpose of transferring the newspapers, one at a time, and from the top of the stack 18, forwardly onto the chute 14, in the manner indicated by broken lines at 19 in Fig. 1:

Within the housing 2, and adjacent but short of the top plate 3, the frame 1 is fitted with a pair of transversely spaced, longitudinal guide rods 20 disposed in parallelism; there being a carriage 21 mounted on said rods for reciprocation.

A flexible cord, indicated generally at 22, such as a flexible metallic cable of light gauge, is adjustably anchored, as at 23, to the carriage 21 intermediate the ends of said cord.

The rearward run 24 of the flexible cord 22 extends in the housing 2 about direction-changing sheaves 25, and thence loops downward about the sheave 26 of a vertically guided counter-weight 27; said run thence extending upwardly to an anchor 28. The counter-weight 27, with the described reeving of the rearward run 24 of the flexible cord acts to normally maintain the carriage 21 in a retracted position in the housing 2.

The forward run 29 of the flexible cord 22 extends forward about direction-changing sheaves 30, and then loops downwardly about the sheave 31 of another vertically guided counter-weight 32; the latter being of substantially less weight than the counter-weight 27.

From the sheave 31 the cord run 29 extends upwardly over a sheave 33, and then passes downward and is secured to the periphery of a relatively large-diameter pulley 34 fitted with a crank handle 35, the latter being accessible on one side of the housing.

The crank handle 35, when manipulated, causes operation of the newspaper feeding unit, and it is contemplated that said crank handle 35 will be coin-controlled, by means of a device not here shown.

A stop 36 is mounted in the housing 2, and in connection with the frame 1, in position to limit upward travel of the counter-weight 32, for the reason which will be hereinafter described.

The carriage 21 includes a rigid depending bracket 37, to which a pair of spaced parallel links 38 are pivoted, as at 39; said links extending at a downward and rearward inclination to connection, pivotally, as at 40, between a pair of vertical guide plates 41 included in a longitudinal body 42 which includes a pair of longitudinally extending bars 43 secured together in fixed relation. The bars 43 are fitted at the front with laterally projecting spindles 44 on which stop rollers 45 are rotatably mounted.

The longitudinal body 42 includes, at the front end of the vertical guide plates 41, a depending lug 46 adapted to depend between a pair of transversely spaced longitudinal rails 47 which extend between the back stop plate 7 and the cross member 15 in a central longitudinal opening 48 in the platform 17.

A rearwardly opening U-shaped yoke 49 is fixed, intermediate its ends, to the lug 46, and said yoke carries a transverse spindle 50. Between the legs of the yoke 49, the spindle 50 includes a rotary spool 51 whose ends are enlarged as rollers 52. At opposite ends the spindle 50 is fitted with radial feed needles 53, one of which

swings rearwardly against a stop pin 54 to normally position said needles at a forward and downward incline toward their points, the latter being at the lower ends of said needles.

The feed needles 53 are yieldable forwardly from their lower ends against the tension of a spring 55; said yielding of the needles being together as they turn jointly with the spindle 50. When a stack of newspapers 18 is disposed on the platform 17, the rollers 52 tend to ride atop said stack, whereas when the machine is empty the rotary spool 51 rides on the rails 47 with the lug 46 depending between said rails.

In operation of the above described newspaper vending machine, the carriage 21 is normally in a retracted position, with the body 42 retracted into abutment with the back stop plate 7. To dispense a newspaper, the crank handle 34 is pulled in the direction indicated by the arrow in Fig. 5, until a radial shoulder 56 on the pulley 34 engages a stop 57. When this occurs the forward run 29 of the cable is relatively shortened, resulting first in the counter-weight 32 rising against its stop 36, and thence in the carriage 21 traveling forwardly through a predetermined stroke on the guide rods 20. At the same time the forwardly and downwardly inclined feed needles 53 bite into the top newspaper of the stack 18, advance it from said stack, and thence deliver it free onto the chute 14; the rollers 52 never running off the forward end of the stack 18. As said fed newspaper falls onto the chute 14 it slides downwardly to engage with the stop fingers 16, where it is accessible for withdrawal by the customer.

With each newspaper dispensing operation, and as the carriage 21 and longitudinal body 42 advance, the stop rollers 45 strike the front stop plate 6 before said carriage reaches its foremost point of advance, as shown in the right-hand dotted-line position in Fig. 1. The result is that when the carriage 21 completes its forward travel, after said stop rollers 45 engage the front stop plate 6, the parallel links 38 cause said body 42 and the mechanism thereon to rise slightly; this to assure that the newspaper being fed freely escapes the feed needles 53 at the forward end of the stroke of the newspaper feeding unit. The stop rollers 45, being anti-friction means, reduce the drag which would otherwise be imposed on the body 42 as it rises.

After a newspaper is so dispensed and the crank handle 35 released, the counter-weight 27, being of greater weight than the counter-weight 32, acts to return all of the parts to their starting positions; the needles 53 merely dragging rearwardly over the top newspaper without penetration, by reason of the downward and forward inclination of said needles and their ability to yield forwardly at their lower ends.

It should here be noted that the arrangement of the parallel links 38 permits the longitudinal body 42, and the parts thereon, to automatically adjust from a high starting position on top of the stack 18 progressively downward as the newspapers are dispensed. Yet by virtue of the compensating counter-weights 27 and 32 in the runs 24 and 29 of the flexible cord 22, the longitudinal body 42 and the parts thereon travel through an equal or constant stroke with successive newspaper dispensing operations, and as is necessary to feed each newspaper effectively from the top of the stack 18 onto the chute 14. In this connection note in the dotted and full line positions of the newspaper feeding unit, in the left hand

portion of Fig. 1, that at different heights of the stack 18 the carriage 21 occupies different longitudinal positions, but in each of such positions the longitudinal body 42 returns fully to its starting position in abutment with the back stop plate 7.

After the last newspaper of the stack 18 has been dispensed, the machine is operative to dispense the display newspaper 10 from the display chamber 8. This is accomplished as follows:

A cross shaft 58 is journaled below the rails 47 adjacent the forward ends thereof, and said cross shaft 58 includes an upstanding trigger 59 which extends between said rails 47. On the next following operation of the crank handle 35 after the last newspaper is dispensed from the stack 18, the rotary spool 51 runs on the rails 47, with the lug 46 traveling between the latter to then engage and trip the trigger 59.

When this occurs, an above-dead center, radial lever 60 on the cross shaft 58 is swung below dead-center, pulling rearwardly on a connecting rod 61 connected to a radial lever 62 on the rotary gate 12, causing opening of the latter. When the rotary gate 12 opens, the display newspaper 10 slides downward against the stop fingers 16 for access by the customer. When the display newspaper 10 has thus been dispensed, subsequent prospective customers know that the machine is empty. The lever 60 is normally maintained at above dead-center by means of a spring-pressed rod unit 63 connected to a lever 64 on the cross shaft 58, which lever 64 normally bears against the front of a stop 65. At the end of the cross shaft 58 opposite the lever 64 there is a reset crank 66. This reset crank 66 is employed for the purpose of re-latching or closing the rotary gate 12 by swinging the lever 60 upwardly to its normal above dead-center position. The reset crank 66 is accessible from the adjacent side of the housing, which includes a door (not shown), and which door is used for the entry or placement of the stack 18 of newspapers into the machine.

Operation of the machine is intended to be controlled by the depositing of a coin in a slot indicated at 67 in Fig. 6, the coin control mechanism forming no part of this invention. It is contemplated, however, that this slot shall be closed by a shutter 68 connected to a lever 69. This lever in turn is connected to a stem 70 associated with spring 63 and connected to lever 64. The shutter 68 and lever 69 are arranged so that when gate 12 is opened to dispense the display newspaper 10, the shutter is moved to close the coin slot 67, thus definitely placing the machine out of service.

The above described newspaper vending machine provides for the ready, convenient, and practical dispensing of newspapers, one at a time to customers, without the need of an attendant; the machine being relatively simple in its structure, economical to manufacture, and having mechanism which is not likely to become out of order.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A newspaper dispensing machine comprising a housing having a delivery opening at the front, a chute in the housing leading to the opening, a newspaper stack platform in the housing to the rear of the chute, a carriage mounted to reciprocate longitudinally above the stack, vertically spaced parallel links pivotally connected to the carriage and extending longitudinally downward at an incline, a newspaper engaging device pivoted to the links at their lower ends, said device normally resting on the top newspaper of the stack in feeding relation thereto, and mechanism connected to the carriage to reciprocate the same from a normally retracted position.
2. A newspaper dispensing machine comprising a housing having a delivery opening at the front, a chute in the housing leading to the opening, a newspaper stack platform in the housing to the rear of the chute, a carriage mounted to reciprocate longitudinally above the stack, vertically spaced parallel links pivotally connected to the carriage and extending longitudinally downward at an incline, a newspaper engaging device pivoted to the links at their lower ends, said device normally resting on the top newspaper of the stack in feeding relation thereto, and mechanism connected to the carriage to reciprocate the same from a normally retracted position; the carriage occupying varying retracted positions dependent on the height of the stack and the resultant inclination of the links, and said mechanism being arranged to compensate for said varying carriage positions.
3. A newspaper dispensing machine comprising a housing having a delivery opening at the front, a chute in the housing leading to the opening, a newspaper stack platform in the housing to the rear of the chute, a carriage mounted to reciprocate longitudinally above the stack, vertically spaced parallel links pivotally connected to the carriage and extending longitudinally downward at an incline, a newspaper engaging device pivoted to the links at their lower ends, said device normally resting on the top newspaper of the stack in feeding relation thereto, and mechanism connected to the carriage to reciprocate the same from a normally retracted position; the carriage occupying varying retracted positions dependent on the height of the stack and the resultant inclination of the links, and said mechanism includes a flexible cord connected intermediate its ends to the carriage, one run of the cord connecting to a pull device and the other run being anchored, and counterweights connected to each run, said counterweights providing compensation in the cord runs for said varying carriage position.
4. A newspaper dispensing machine comprising a housing having a delivery opening at the front, a chute in the housing leading to the opening, a newspaper stack platform in the housing to the rear of the chute, a carriage mounted to reciprocate longitudinally above the stack, vertically spaced parallel links pivotally connected to the carriage and extending longitudinally downward at a rearward incline, a newspaper engaging device pivoted to the links at their lower end, said device including an element normally resting on the top newspaper of the stack in feeding relation thereto, mechanism connected to the

carriage to reciprocate the same from a normally retracted position to a fully advanced position; and cooperating stop means between the device and housing to cause said device to halt in its advancing movement before the completion of advancing movement of the carriage while allowing of upward movement of the device whereby upon movement of the carriage to its fully advanced position the links will swing to raise the device clear of the fed top newspaper so as to free it onto said chute.

5. A newspaper dispensing machine, as in claim 4, in which said stop means includes a transverse axis roller on the device, and a cooperating upstanding plate fixed in the housing, the roller reducing the friction of said raising of the device.

6. A newspaper dispensing machine comprising a housing having a delivery opening at the front, a chute in the housing leading to the opening, a newspaper stack platform in the housing to the rear of the chute, a normally retracted, reciprocating, newspaper feeding device adapted to seat on the top newspaper of the stack in feeding relation thereto, said device being mounted for vertical floating to lower upon successive reduction in the height of the stack, manually controlled mechanism to reciprocate said device, the machine including a housing having a newspaper display chamber at the front, a normally closed gate at the bottom of the chamber to retain a display newspaper, the gate when opened delivering the display newspaper to the chute, and means to open the gate upon the actuation of the mechanism following its actuation to feed the last newspaper of the stack.

7. A newspaper dispensing machine comprising a housing having a delivery opening at the front, a chute in the housing leading to the opening, a newspaper stack platform in the housing to the rear of the chute, a normally retracted, reciprocating, newspaper feeding device adapted to seat on the top newspaper of the stack in feeding relation thereto, said device being mounted for vertical floating to lower upon successive reduction in the height of the stack, manually controlled mechanism to reciprocate said device, the machine including a housing having a newspaper display chamber at the front, a normally closed gate at the bottom of the chamber to retain a display newspaper, the gate when opened deliver-

ing the display newspaper to the chute, and means to open the gate upon the actuation of the mechanism following its actuation to feed the last newspaper of the stack; said last named means including a trigger positioned to be engaged and advanced by the newspaper feeding device upon reciprocation thereof from the position it occupies only after feeding of said last newspaper from the stack.

8. A newspaper dispensing machine comprising a housing having a delivery opening at the front, a chute in the housing leading to the opening, a newspaper stack platform in the housing to the rear of the chute, a carriage mounted to reciprocate longitudinally above the stack, vertically spaced parallel links pivotally connected to the carriage and extending longitudinally downward at an incline, a newspaper engaging device pivoted to the links at their lower ends, said device normally resting on the top newspaper of the stack in feeding relation thereto, manually controlled mechanism to reciprocate said device, the machine including a housing having a newspaper display chamber at the front, a normally closed gate at the bottom of the chamber to retain a display newspaper, the gate when opened delivering the display newspaper to the chute, and means to open the gate upon the actuation of the mechanism following its actuation to feed the last named newspaper of the stack; the device resting on the platform after feeding of the last newspaper from the stack, and said last named means including a trigger to be engaged and advanced by the newspaper feeding device upon reciprocation thereof from said position of rest on the platform.
